Primary Examiner — Anhdao Doan

(73) Assignee: **Hitachi High-Technologies Corporation**, Tokyo (JP)

(74) Attorney, Agent, or Firm — Antonelli, Terry, Stout & Kraus, LLP.

(**) Term: **14 Years**

(57) **CLAIM**

We claim the ornamental design for a sample tube holder stocker for clinical laboratory automation system, as shown and described.

(21) Appl. No.: **29/411,274**

DESCRIPTION

(22) Filed: **Jan. 19, 2012**

(30) **Foreign Application Priority Data**

Sep. 30, 2011 (JP) 2011-022524

FIG. 1 is a front, top and right side perspective view of a sample tube holder stocker for clinical laboratory automation system showing our new design;

(51) **LOC (9) Cl.** **24-01**

FIG. 2 is a front elevational view thereof;

(52) **U.S. Cl.**

FIG. 3 is a rear elevational view thereof;

USPC **D24/216**

FIG. 4 is a left side elevational view thereof;

(58) **Field of Classification Search**

FIG. 5 is a right side elevational view thereof;

USPC D24/216, 217, 219, 231, 232, 107,

FIG. 6 is a top plan view thereof; and,

D24/169, 186; D10/81; 422/62-65, 67; 436/43,

FIG. 7 is a bottom plan view thereof;

436/45, 47

FIG. 8 is a right side elevational view thereof showing in an opened position;

See application file for complete search history.

FIG. 9 is a cross sectional view taken along the lines 9-9 of FIG. 2; and,

(56) **References Cited**

FIG. 10 is a cross sectional view taken along the lines 10-10 of FIG. 5.

U.S. PATENT DOCUMENTS

The broken lines in the drawing views are included for the purpose of illustrating portions of the sample tube holder stocker for clinical laboratory automation system that form no part of the claimed design.
